SPINNING AND TWISTING FRAME

Application filed September 13, 1927, Serial No. 219,304, and in Great Britain September 20, 1926.

This invention relates to spinning, twisting and like frames and more especially to the automatic stop motion employed for arresting a machine when the bobbins are full, thereby ensuring that each doffing shall be of uniform weight and length; and the invention has for its objects, to overcome the present difficulty in starting up a machine, to provide a less costly and less complicated motion capable of being installed in a smaller space than the existing type, to enable a frame to be started up in the ordinary way without interfering with the setting of the stop motion, and to permit the stop motion at one side 15 of a frame to be operated independently of the setting of that at the opposite side.

In existing stop motions operating through the medium of a coarse starting screw the belt is liable to be strained, and when a double 20 thread screw is employed (as is commonly the case) difficulty in starting up is experienced. The use of this coarse thread or of a double thread is now obviated.

According to the invention the starting rod 25 of spinning, twisting and like frames is engaged, while the frame is running, by a retaining catch controlled by a flexible connection coupling it to a member of the knock-off motion and adapted to be released thereby at 30 a predetermined time to permit the starting rod to move to shift the driving belt or otherwise to arrest the machine.

In its preferred form the invention embodies a spring-controlled retaining catch 35 which may be borne pivotally by the sliding member adapted to travel as a nut on the fine threaded rod supported in a bracket fixed to the frame and provided with an operating hand-wheel, whilst a flexible connection such 40 as a chain or a Bowden wire may connect said retaining catch with a lever mounted pivotally in the path of a projection on a member of a spool-type knock-off motion, or, alternatively, said chain or wire may be connected to the lever of a length-type knock-off motion.

Also, in the preferred form, the end of said starting rod may be formed with a notch, lug or the like, adapted to be engaged directly 45 by the aforesaid retaining catch which, when

the sliding member is travelled as a nut by operating the aforesaid hand wheel, serves to draw the starting rod into the starting up position.

One constructional embodiment of the invention as applied to a worsted spinning frame is illustrated by way of example in the accompanying drawings, in which, Figure 1 is an end view, Figure 2 is a side elevation, and Figure 3 is a plan view, only such parts of the frame as are necessary for describing the function of the invention being shown.

A is the longitudinally movable starting rod connected to and operating the belt fork A¹ and harnessed to a spring A² suitably anchored to the main frame of the machine (or if desired, to a weight instead of a spring), and A³, A⁴, are respectively, the fast and loose pulleys mounted on the main driving shaft A⁵.

The starting rod A is supported near its outer end by an eye A⁶ connected to a bracket A⁷ secured to the endstand K, and said starting rod is formed with a hooked extremity A⁸ adapted to be engaged by the nose of a catch B mounted pivotally at B¹ upon a projection or horn B² springing from an internally screw-threaded block C adapted to work as a nut upon a finely threaded rod D supported rotatably in bearings D¹, D², and at its outer end carrying an operating hand-wheel D³. The block C is formed with a base C¹ resting on and adapted to slide along the upper surface of the bracket A⁷.

The horn B² terminates in a pair of apertured ears B³, B³, between each of which and the body of the catch B a spring B⁴ is confined, and into each of said ears B³ is screwed a sleeve or gland B⁵ supporting one end of the flexible casing B⁶ of a Bowden wire B⁷ that end of which is sweated or otherwise suitably secured to the catch B.

The casing B⁶, containing wire B⁷, is carried from each of said ears B³ down the endstand K through supporting clips, lugs B⁸ or otherwise suitably, and is secured to a sleeve or gland B⁹ fixed in a bracket B¹⁰ bolted to the main framing, the extremity of the wire B⁷ being sweated or otherwise suitably attached to a trip lever E pivoted at E¹ to

bracket B¹⁰ and projecting into the path of movement of a stop or projection F carried by a longitudinally movable member F¹ of the traversing lifter mechanism and functioning as a spool-type knock-off motion.

5 The connections from B³ to E and the parts F, F¹, are of course duplicated although omitted in the drawings.

Instead of connecting the lower end of the 10 Bowden wire B⁷ or its equivalent to a spool-type knock-off motion as shown, the wire may be connected to the gear-operated lever of a length-type knock-off motion, as will be well understood.

15 In operation, when the machine is standing the belt fork A¹ would be over pulley A⁴ and the hooked end A⁸ of the starting rod A would be adjacent to the supporting eye A⁶.

In order to start up the frame the hand-wheel D³ is turned so as to travel the block 20 C along the finely threaded rod D until the catch B is engaged with the hooked end A⁸ of rod A. The movement of hand-wheel D³ is then reversed and rod A is drawn by catch 25 B longitudinally to the left, transferring the driving belt slowly from loose pulley A⁴ to driving pulley A³.

When the block C reaches the end of its 30 sliding movement to the left the parts are in the running position and remain so until the time arrives for the lever E to be struck by projection F thus pulling wire B⁷ and releasing catch B from the hooked end A⁸. Immediately catch B is withdrawn the rod A 35 moves under the influence of spring A⁸ to the right and transfers the belt to loose pulley A⁴ thus stopping the frame.

Until the bobbins are full and the frame is knocked-off the hooked end of the starting 40 rod and the spring-controlled catch remain in engagement, and if necessary, during the intervening period such as at meal times, the frame may be stopped and re-started in the ordinary manner.

45 The invention is obviously applicable to machines other than spinning and twisting frames.

What I claim is:—

1. In a spinning, twisting and like frame 50 having a starting rod, belt-shifting means actuated by said starting rod and also having a traversing lifter mechanism, a retaining catch engageable with said starting rod and mounted adjustably relatively thereto, a trip 55 member borne movably by a stationary part of said frame adjacent to and operable by the movement of a member of said traversing lifter mechanism, a flexible cable connecting said retaining catch with said trip member, and means to trip said retaining catch to disengage same from said starting rod.

2. In a spinning, twisting and like frame 60 having a starting rod, belt-shifting means actuated by said starting rod and also having a traversing lifter mechanism, a spring- 65

controlled retaining catch engageable with said starting rod and mounted adjustably relatively thereto, a trip member borne movably by a stationary part of said frame adjacent to and operable by the movement of a member of said traversing lifter mechanism, a flexible cable connecting said retaining catch with said trip member, means to trip said retaining catch to disengage same from said starting rod, and a spring to move said starting rod when disengaged from said retaining catch.

3. In a spinning, twisting and like frame having a starting rod, belt-shifting means actuated by said starting rod and also having a traversing lifter mechanism, a hooked end to said starting rod, a spring-controlled retaining catch engageable with said hooked end of said starting rod and mounted adjustably relatively thereto, a trip member borne movably by a stationary part of said frame adjacent to and in operative association with a member of said traversing lifter mechanism, a flexible cable connecting said adjustably mounted retaining catch with said trip member, a stop member to trip said retaining catch to disengage same from said hooked end of said starting rod, and a spring to move said starting rod when disengaged from said retaining catch.

4. In a spinning, twisting and like frame having a starting rod, belt-shifting means actuated by said starting rod and also having a traversing lifter mechanism, a hooked end to said starting rod, a spring-controlled retaining catch engageable with said hooked end of said starting rod, said spring-controlled retaining catch being mounted on a member travelling as a nut on a finely threaded rod, a handwheel upon said finely threaded rod to adjust said retaining catch, a trip member borne movably by a stationary part of said frame adjacent to and in operative association with a member of said traversing lifter mechanism, a flexible cable connecting said retaining catch with said trip member, and a stop borne by said member of said traversing lifter mechanism and serving to trip said retaining catch to disengage same from said hooked end of said starting rod.

5. In a spinning, twisting and like frame having a starting rod, belt-shifting means actuated by said starting rod and also having a traversing lifter mechanism, a hooked end to said starting rod, a spring-controlled retaining catch engageable with said hooked end of said starting rod to retain same for a determined period, said spring-controlled retaining catch being mounted on a member travelling as a nut on a finely threaded rod, a hand-wheel upon said finely threaded rod to adjust said retaining catch, a trip lever borne pivotally by a stationary part of said frame adjacent to and in operative association with a movable member or said traversing lifter

mechanism, a flexible cable connecting said retaining catch with said pivotally mounted trip lever, and a stop borne by said movable member of said traversing lifter mechanism and serving to move said pivotally mounted trip lever to trip said retaining catch to disengage same from said hooked end of said starting rod.

5 In testimony whereof he affixes his signature.
